Monroe B. Levoy, Great Neck, N.Y., assignor to Optical
Salons Ltd., Great Neck, N.Y., a corporation of Delaware

Application June 20, 1958, Serial No. 51,448

Term of patent 14 years

(Cl. D57—1)

Fig. 4.

Fig. 1 is a side elevational view of a combined spectacle frame and hair ornament, showing my new design;

Fig. 2 is a front perspective view thereof;

Fig. 3 is a top plan view thereof; and

Fig. 4 is an enlarged detail view of the hair ornament portion thereof.

The dominant features of my design reside in the portions shown in the full lines on the drawings.

I claim:

The ornamental design for a combined spectacle frame and hair ornament, as shown and described.
